(57) CLAIM

The ornamental design for a spacer for pavers, as shown and described.

DESCRIPTION

FIG. 1 is a perspective view of a spacer for pavers showing my new design;

FIG. 2 is a bottom view of the design of FIG. 1;

FIG. 3 is a front elevation view of the design of FIG. 1;

FIG. 4 is a side elevation view of the design of FIG. 1; and,

FIG. 5 is a perspective view of the design of FIG. 1.

The broken lines depict portions of the spacer for pavers that form no part of the claimed design.
